UNITED STATES PATENT OFFICE.

WILLIAM C. JOHNSON, OF NEW HAVEN, CONNECTICUT.

PENCIL-SHARPENER.

1,393,378.

Specification of Letters Patent. Patented Oct. 11, 1921.

Application filed March 13, 1920. Serial No. 365,395.

To all whom it may concern:

Be it known that I, WILLIAM C. JOHNSON, a citizen of the United States, residing at New Haven, in the county of New Haven and State of Connecticut, have invented a new and useful Improvement in Pencil-Sharpener; and I do hereby declare the following, when taken in connection with the accompanying drawings and the characters of reference marked thereon, to be a full, clear, and exact description of the same, and which said drawings constitute part of this application, and represent, in—

Figure 1, a view in vertical central section of a pencil-sharpener constructed in accordance with my invention.

Fig. 2, a view thereof in vertical transverse section on the line 2—2 of Fig. 1, and looking inward toward the cutters.

Fig. 3, a view in central horizontal section on the line 3—3 of Fig. 2.

Fig. 4, a detached plan view of the cutter-carrier showing the cutters by broken lines.

Fig. 5, a detached plan view of the cutter-carrier shown as turned a quarter-turn from the position in which it is shown in Fig. 4.

Fig. 6, a detached end view of one of the cutters.

Fig. 7, a detached broken perspective view of the chip-receptacle.

My invention relates to an improved pencil-sharpener of the type employing two cutters mounted in inclined positions in a revolving cutter-carrier, the object being to produce a simple, convenient, and efficient pencil-sharpener constructed with particular reference to supporting the point of the pencil when the cutting is going on, whereby the breaking of the lead is reduced to the minimum, to permitting the point to be observed during the cutting operation thus avoiding the unnecessary cutting away of the pencil, to providing for readily setting the device as a whole at any convenient angle, and to readily adjusting the cutters to take up the wear on the bearings.

With these ends in view, my invention consists in a pencil-sharpener having certain details of construction as will be hereinafter described and pointed out in the claims.

In carrying out my invention as herein shown, I employ a two-part case or housing consisting of complementary parts 4 and 5 provided with offsetting lugs 6 by means of which they are fastened together by screws 7, the case-part 5 being formed with an in-

tegral, inclined, outwardly extending sleeve 8 providing a bearing for the shaft 9 the outer end of which carries a handle-lever 10 thus located in front of the said case and 60 furnished with a handle-grip 11.

Within the said two-part case, I journal a skeleton-like cutter-carrier provided at its outer end with a hollow pencil-point-receiving trunnion 12 having bearing in a projecting bearing-sleeve 13, the semi-circular halves of which are formed integral with the respective case-parts 4 and 5. At its inner end, the said cutter-carrier is formed

with a solid trunnion 14 entering a bearing-hole 15 formed in the conical two-part trunnion 16 by which the device as a whole is supported, as will be described later on, and which consists of two half-cones respectively

cast integral with the case-members 4 and 5. Adjacent to the conical trunnion 16, the cutter-carrier is formed with an annular flange 17 which bears upon the inner face of the two-part conical trunnion 16, as

clearly shown in Fig. 3, and takes the end- 75

wise thrust imposed upon the cutter-carrier when the pencil is inserted into the hollow-trunnion 12 and pressed inward into the device.

Near its outer end, the cutter-carrier is 85 formed with integral complementary arms 18 located opposite each other, inclined from front to rear, and carrying screw-pivots 19,

the pointed inner ends of which respectively enter corresponding conical recesses 20 90

formed in the outer ends of a pair of complementary conical cutters 21, the inner ends (Fig. 1) of which are formed with conical recesses 22 for the reception of pivot-pins

23 having conical heads and mounted in inclined positions in the bottom of a conical observation-chamber 24 formed at the inner end of the cutter-carrier between the annular thrust-taking flange 17 and the bevel-gear 25 thereof. The said flange 17 and bevel-

gear 25 are joined by integral inclined arms 26 forming, as it were, a skeleton-structure inclosing the observation-chamber 24 into

which the inner ends of the cutters 21 extend and in which the extreme point of the pencil is sharpened. The arms 18 of the cutter-carrier and the bevel-gear 25 thereof are in turn united by two integral parallel arms 27 shown in transverse section in Fig.

2, the pencil-receiving space 28 between these 110 arms 27 being in line with the pencil-receiving bore or passage 29 of the hollow-trun-

nion 12 at the outer end of the cutter-carrier.

It will be observed by reference to Fig. 4 that, as aforesaid, the cutters 21 extend rearward through the bevel-gear 25, projecting sufficiently through the same into the observation-chamber 24 to permit the extreme point of the pencil to be under constant observation while it is being sharpened, where-
10 by any unnecessary cutting away of the pencil is avoided. As shown, the cutters 21 are slightly overlapped, but this is no feature of my present invention.

The cutting-edges or lands, of the conical cutters 21 are uniform in width, but progressively decrease in their separation from each other, from the outer to the inner ends of the cutters, as shown in Fig. 6. By thus contracting the spaces between their cutting
20 edges or lands, the lands are adapted to support the exposed portion of the lead and the adjoining beveled portion of the wood in such a manner as to in large part resist the side-thrust which so frequently break the lead, in pencil sharpeners of the type to which my invention belongs.

For revolving the cutter-carrier and the cutters, I employ a driving-pinion 30 mounted upon the inner end of the handle-shaft 9 and meshing into the bevel-gear 25 of the cutter-carrier, and also into the crown-teeth 31 of an annular crown-wheel 32 having a circumferential rib 33 running in an internal peripheral groove 34 formed within the two parts 4 and 5 of the case, in which the said crown-wheel is rotated by the driving pinion 30. The spur-teeth 35 of the said crown-wheel mesh directly into the teeth formed by the forward terminals of the cutting edges
40 of the cutters, as shown in Fig. 2.

When the handle of the device is turned, the cutter-carrier is rotated, whereby the cutters journaled therein are bodily rotated with it in the same direction, while they are
45 additionally rotated toward each other in the opposite direction by the rotation of the crown-wheel 32 which is also driven directly by the pinion 30, as described. I am thus enabled to independently rotate the cutters
50 at a relatively high speed with reference to the speed of their bodily rotation with the cutter-carrier, with the result of securing a shearing rather than a tearing cutting of the lead and wood of the pencil and so protect-
55 ing the point thereof.

In this connection, I may call attention to the fact that the handle comprising the lever 10 and grip 11, by being located on one side of the device and in effect in front of its case, rather than at the inner end thereof, permits the device to be installed and operated with more economy of space than when the handle is located at one of its ends, which is the customary way. In cases where the device is
65 applied to a wall rather than to a table or

desk, it will be found particularly convenient to have the handle arranged in front of the case rather than at its end.

The two-part case of the device is mounted through the medium of its conical two-part trunnion 16 in conical bearing 36 made integral with the upper end of a stand 37 having a circular base 38 by means of which it is secured to the top of the desk or other support. A thumb-screw 39 having a bearing-flange 40 and a threaded-stem 41 is employed for securing the trunnion 16 in the conical bearing 36 either in the vertical position of the case in which it is shown in Fig. 2, or at any desired angle, the operation of the stem 41 which enters a threaded hole in the said trunnion, being to draw the face of the same into the conical bearing 36 so as to firmly bind it therein. I am thus enabled to set the case at any angle desired, with respect to the stand 37 or to line it up therewith. Thus, when the device is applied to a wall or vertical surface, its standard 17 will be in the horizontal plane and its two-part case swung on its two-part trunnion 16 in the conical bearing 36 so as to bring the case itself into the vertical plane.

For the reception of the chips, I employ a basket-like chip-receptacle 42 furnished at its upper end upon its respective parallel side edges with laterally yielding suspension lips 43 engaging with parallel longitudinal ribs 44 upon the lower edges of the sides of the case-parts 4 and 5 as shown in Fig. 2. This construction enables the chip-receptacle to be applied to or removed from the case by a simple sliding movement.

The cutter-carrier is formed with the usual conical pencil-guide 45 in line with the hollow pencil-point-receiving trunnion 12 and 105 also with the pencil-receiving space 28 aforesaid.

I claim:

1. A pencil-sharpener having a cutter-carrier, two conical cutters tapering from 110 end to end mounted in the said carrier at an angle with respect to each other for the initial insertion of the pencil between their larger ends, and means for driving the said cutter.

2. In a pencil-sharpener, the combination with a cutter-carrier, of two cutters mounted therein, a gear mounted upon the cutter-carrier for the rotation thereof and adapted to have the smaller ends of the cutters 120 passed through it and the said carrier being skeletonized adjacent to the projecting smaller ends of the cutters to permit the point of the pencil to be observed during the cutting operation.

3. In a pencil-sharpener, the combination with a cutter-carrier, of two cutters mounted therein in inclined positions for the initial insertion of the pencil between their larger ends, and a gear interposed between 130

and connecting the respective ends of the carrier and adapted to have the smaller ends of the cutter passed through it, the carrier being skeletonized to permit the observation 5 of the point of the pencil while the same is being sharpened.

journaled for rotation therein, two cutters mounted in the said carrier, and means for bodily rotating the said carrier and for independently rotating the said cutters in the opposite direction from which they are rotated by the carrier, the said means including an annular gear mounted within the said case so as to rotate therein. 55

60

4. A pencil-sharpener having a cutter-carrier comprising a hollow-trunnion located at its outer end, cutter-supporting 10 arms, a rear trunnion, a bevel-gear, arms connecting the said outer trunnion and gear with a pencil-receiving space between them, and arms connecting the said rear trunnion and bevel-gear to form an observation-chamber 15 which receives the inner ends of the cutters which pass through the said gear.

65

5. In a pencil-sharpener, the combination with a case provided with a conical trunnion, pencil-cutting means installed within the said

20 case, a standard provided at its upper end with a conical bearing for the reception of the said conical trunnion, and means for

securing the said trunnion in any desired 25 position within the said conical bearing.

6. In a pencil-sharpener, the combination with a two-part case one part of which is

provided with an inclined bearing-sleeve, of a cutter-carrier journaled in the said case, cutters mounted in the said carrier, a bevel-

30 gear carried by the cutter-carrier, a crown-

wheel mounted in the case and engaging with the cutters for rotating the same, a handle-shaft mounted in the said bearing-

35 sleeve, a gear mounted upon the said shaft and engaging with the said bevel-gear and

crown-wheel, whereby the cutter-carrier and the cutters are simultaneously rotated, and

means for mounting the said case. 40

7. In a pencil-sharpener, the combination with the case thereof, of pencil-sharpening

means installed therein, and a chip-receptacle removably applied to the lower end of

the said case from which it is removable 45 and replaceable by longitudinal movement

with respect thereto, the parallel side edges

of the said receptacle being formed with laterally yielding suspension-lips, adapted

to have sliding engagement with parallel

longitudinal ribs upon the lower edges of

50 the case.

8. In a pencil-sharpener, the combination with the case thereof, of a cutter-carrier

55

journaled for rotation therein, two cutters

mounted in the said carrier, and means for

bodily rotating the said carrier and for in-

dependently rotating the said cutters in the

opposite direction from which they are ro-

tated by the carrier, the said means includ-

ing an annular gear mounted within the

said case so as to rotate therein. 60

9. In a pencil-sharpener, the combination with the case thereof, of a cutter-carrier journaled therein, two cutters journaled in

the said carrier, a gear carried by the car-

rier, an annular gear mounted within the

said case for rotation therein and arranged

to rotate the said cutters toward each other

in the opposite direction from which they

are rotated by the carrier, and a driving-

pinion engaging with the gear carried by

70 the said cutter-carrier and the said annular

gear.

10. In a pencil-sharpener, the combination with the case thereof, of a cutter-carrier

journaled therein, two cutters journaled in

the cutter-carrier, a gear carried by the car-

rier, an annular gear mounted within the

case for rotation therein and having teeth

engaging directly with the said cutters for

rotating the same toward each other inde-

pendently of the rotation of the carrier, a

handle-shaft mounted in the said case, and

a driving-pinion connected with the said

handle-shaft and meshing directly into the

80 gear of the cutter-carrier and into the said

annular gear. 85

11. In a pencil-sharpener, the combination with the case thereof, of a cutter-carrier

journaled therein, two cutters journaled in

the said carrier, and means for revolving

90 the cutters toward each other at a greater

speed than the speed at which they are

bodily rotated with the cutter-carrier in-

cluding an annular crown gear rotating

upon its periphery, within the said case, and

95 directly engaging the said cutters.

In testimony whereof, I have signed this specification in the presence of two subscribing witnesses.

WILLIAM C. JOHNSON.
